EMIL L. PFUNDER, OF HARTFORD, CONNECTICUT, ASSIGNOR TO UNDERWOOD
TYPEWRITER COMPANY, OF NEW YORK, N. Y., A CORPORATION OF NEW
JERSEY.

TYPE-WRITING MACHINE.

1,089,075.

Specification of Letters Patent. Patented Mar. 3, 1914.

Application filed January 16, 1908. Serial No. 411,084.

To all whom it may concern:

Be it known that I, EMIL L. PFUNDER, a citizen of the United States, residing in Hartford, in the county of Hartford and State of Connecticut, have invented certain new and useful Improvements in Type-Writing Machines, of which the following is a specification.

My invention relates to devices for shifting the platen carriers or other case-shifting devices of typewriting machines, to change from lower to upper case.

Heretofore two independent shift keys have been provided, one at each side of the keyboard. Usually the right-hand key shifted the platen to upper case and locked it there, while the left-hand shift key served to release the platen.

One of the principal objects of my invention is to provide increased facilities for shifting the platen and platen frame or other case-shifting device, and particularly to increase the convenience of effecting a temporary shift of the platen, without however sacrificing the usual advantage of locking the platen by the mere depression of a shift-key.

A further object of the invention is to increase the facility for releasing the platen or shift mechanism when it has been locked.

To these ends I contrive to elevate or shift the platen or platen frame by means of a temporary shift-key at either side of the keyboard, so that either of said keys may be depressed and held down during the writing of a single capital letter, and then released to restore the shift mechanism to normal lower-case position. In addition to said keys, I provide a third key, preferably at the right-hand side of the keyboard, which may be depressed to both shift and lock the platen in upper-case position. This lock may be released by depression of either of the first-mentioned temporary shift keys.

In carrying out my invention in its preferred form, I arrange at the right-hand side of the keyboard a shift-lever whose key stands preferably in the second bank of keys. A dog provided upon the machine-frame catches said lever upon the depression thereof, to lock it down. Upon said shift-lever I pivot a short lever bearing a key in the front bank of keys, and this front key-lever has a finger to release the

dog. It will be understood that this short lever serves to bear down the first key-lever to shift the platen. In other words, the platen may be shifted and held locked by the first-mentioned key, or it may be shifted temporarily by the second-mentioned key, since the finger on the latter silences the dog or holds it out of action. At the left-hand end of the keyboard is the usual temporary shift key, having a connection to release said dog, this shift-key being arranged as usual in the front bank of keys. Thus the operator may temporarily shift the platen without locking the same, by depression of either of the keys that are mounted at the ends of the front bank of keys, thereby greatly facilitating the operation of the machine; while at any time the platen may be shifted and locked by merely depressing the locking key; and thereafter the platen may again be released by depressing either one of the aforesaid temporary shift keys.

In the accompanying drawings, Figure 1 is a perspective view showing the platen and one form of my improved shifting devices. Fig. 2 shows the shift-and-lock key lever. Fig. 3 is an elevation of the right hand end of the platen and the shifting and locking devices at this point, showing the elements in normal lower-case position. Fig. 4 is a similar view showing the platen locked in upper case position. Fig. 5 is a fragmentary view illustrating the action of the right-hand temporary shift-key. Fig. 6 shows the right-hand temporary shift key that releases the locking dog.

Type bars 1 carry upper and lower case types to strike upon the front of a platen 2, which is mounted in a platen frame 3, the latter supported upon a carriage 4. The platen frame is shiftable up and down by means of a rocking frame 5 having a horizontal rail 6, whereon runs a roll 7 of the platen frame 3.

A temporary shift key 8, at the left hand side of the machine is mounted upon the forward end of a lever 9 pivoted loosely upon a rod 10, and having an upstanding arm 11 to engage a pendent arm 12 of the rocking frame 5 to lift the platen frame. By depressing said key, the type keys are caused to write capital letters, and upon releasing the key 8, the platen is dropped to normal position, so that the keys will write lower case

2

letters. At the right hand side of the machine is a similar arm 11 to operate a similar arm 12 of the rocking frame, said arm 11 extending out from a lever 13, which is loosely pivoted upon the rod 10, and carries at its forward end a key 14, depression of which will throw the platen frame up to the dotted line position, at Fig. 1. When the key 14 is depressed, a hook or dog 15 catches over a pin 16 which projects from the side of the lever 13, thereby holding down said lever and holding the platen in the upper position, so that a line of capital letters may be written. The dog 15 is rigidly secured upon a rock shaft 17, and a spring 18 tends constantly to move the dog 15 backwardly, so that it will catch over the pin 16 when the latter is sufficiently depressed. Said temporary shift key 8 has means to release the lever 13 from the control of the dog 5, so as to permit the platen frame to drop. A pin 19 projects from the side of the lever 9 to engage an upstanding cam arm 20 also fixed upon the rock shaft 17, so that at every depression of said key 8, the shaft 17 is rocked and the dog 15 carried forwardly, thereby releasing the pin 16 and lever 13 and permitting the platen frame to drop.

I pivot at 21 upon the shift key lever 13 an auxiliary short lever 22 bearing a key 23, which is in front of the locking key 14. The lever 22 extends back from the fulcrum 21, and is formed with ears 24, 25, to catch over the top and bottom of the lever 13 to limit the play of lever 22 thereon. The auxiliary lever 22 is also formed with a downwardly extending finger 26, the rear edge 27 whereof engages a pin 28 provided upon the dog 15 below the rock shaft 17. Depression of the key 23 turns the auxiliary lever 22 about the pivot 21, and the finger 26 is swung backwardly to engage pin 28, and thereby rock the dog 15 forwardly to an idle position, preventing it from catching over the pin 16 on the shift lever 13. Hence the key 23, as well as the key 8, may be used to release the lever 13 from the control of the dog. The key 23 may also be used as a temporary shift key in the same manner as the key 8, since the ear 24 enables the key 23 to swing down the lever 13, while the finger 26 silences the dog 15, so that when the key 23 is released, the platen frame drops.

The keys 8 and 23 are at the extreme ends 55 of the front bank of type keys 29. The next rear bank is seen at 30, the next at 31, and the rearmost bank at 32, Fig. 3. The key 14 is preferably in the next to the rear bank, that is, at the right hand end of the bank 60 of keys 31. Thus, shift key 14 may be depressed at any time to shift and lock the platen frame, while either key 8 or 23 may be employed to unlock the same. Moreover, either of said keys 8 or 23 may be used at 65 any time as a temporary shift key.

Having thus described my invention, I claim:

1. In a typewriting machine, the combination with a case-shifting member, of a key lever at each side of the keyboard to 70 shift said shifting member, a dog to lock one of the key levers, means connecting the other key lever with the dog to release the same upon operation of said other or second key lever, and an auxiliary key lever hung 75 on the first key lever to release the dog.

2. In a typewriting machine, the combination with a case-shifting member, of a key lever at each side of the keyboard and operable independently of each other to 80 shift said shifting member, a dog to lock the first of the levers, means to enable the other of said key levers to release the dog, and an extra key also carried on the first key lever and having means to release the 85 dog.

3. In a typewriting machine, the combination with a shiftable member, of a key to shift the same, a dog to lock the key, an auxiliary key hung on the first key to release the dog, and a separate key movable independently of the first key, to both shift said shiftable member and release said dog. 90

4. In a typewriting machine, the combination with a shiftable member, of a key 95 lever to shift the same, a pivoted dog to lock the key lever, and an auxiliary key lever fulcrumed between its ends on the first key lever, one end of the auxiliary lever bearing a key, and the other end engaging the 100 dog to release it.

5. In a typewriting machine, the combination with a case-shifting member, of a key lever to shift the carriage, a dog to lock the key lever, and an auxiliary key lever intermediately fulcrumed on the first key lever, the outer end of the auxiliary key lever bearing the key and the inner end cooperating with the dog to release it; a third key lever removed from the first key lever 105 and also adapted to shift said case-shifting member, and devices actuated by the third key lever also to release the dog. 110

6. In a typewriting machine, the combination with a shiftable member, of a key 115 lever to shift the same, a dog to lock the key lever, an auxiliary key lever fulcrumed on the first key lever and having means to release the dog; a third key lever removed from the first and also connected to shift the shiftable member, a rock-shaft on which the dog is mounted, and means for operating the rock-shaft from the third key lever. 120

7. In a typewriting machine, the combination with a shiftable member, of a key lever to shift the same, means to lock the key lever depressed, a second key movable independently of said key lever having 125 means either to depress said key lever and 130

simultaneously silence the locking means, or to release the key lever from the locking means; a third key lever, and devices also actuated by the latter to release the locking means.

8. In a typewriting machine, the combination with a carrier and platen, of a key lever to shift the carrier, means to lock the key lever when individually depressed, an auxiliary key lever having limited independent motion on the first key lever, the auxiliary key lever controlling the locking means, whereby after the first key lever is individually depressed, depression of the auxiliary key lever will release the same, and whereby when the first key lever is depressed through the medium of the auxiliary key lever the locking means will be held inactive.

20 9. In a typewriting machine, the combination with a carrier and platen, of a key lever to shift the carrier, a dog mounted independently of the key lever, one end of the dog mounted to engage a part on the key lever to lock the latter in depressed position, and an auxiliary key lever having limited pivotal movement on the first key lever, the auxiliary lever having at its inner end a finger co-acting with a second end of the dog to release the same.

10. In a typewriting machine, the combination with the carriage and platen, of a key lever to shift the same, a pin on the key lever, a yielding intermediate pivoted dog having at its upper end a hook to engage the pin, an auxiliary key lever fulcrumed on the first key lever and having at its inner end lips engaging opposite edges of the first key lever to limit independent motion of the auxiliary key lever, and a downwardly disposed finger on the auxiliary key lever to release the dog.

11. In a typewriting machine, the combination with a carrier and a platen, of a key lever to shift the carrier, a pin on the key lever, a yielding pivoted dog having at its upper end a hook to engage the pin, an auxiliary key lever fulcrumed on the first key lever and having at its inner end lips engaging opposite edges of the first key lever to limit independent motion of the auxiliary key lever, a downwardly disposed finger on the auxiliary key lever to engage and release the dog, a third key lever having means to shift the carriage, and a connection between the third key lever and the dog.

12. In a typewriting machine, the combination with a case-shifting member, of keys operable independently of each other to shift said shifting member, a dog to lock one of the keys together with said shifting member, means connecting the other key with said dog to release the same, and an auxiliary key connected to one of said keys

both to shift said shifting member and release the dog.

13. In a typewriting machine, the combination with a shiftable member, of a key to shift the same, a dog to lock the key, an auxiliary key hung on the first key to shift said shiftable member and release the dog, and a separate key operable independently of the first key to both shift said shiftable member and release said dog.

75 14. In a typewriting machine, a case-shifting mechanism comprising a member to be shifted, a shift lever, a dog to catch upon said lever upon the depression thereof to lock it down, and an auxiliary short lever pivoted upon said shift lever and extending forwardly therefrom and having a key, and also having a finger to release said dog; said auxiliary lever capable of operating the first lever to shift said shiftable member.

80 15. In a typewriting machine, a case-shifting mechanism comprising a member to be shifted, a permanent shift lever, a dog to catch upon said lever upon the depression thereof to lock it down, an auxiliary short lever pivoted upon said shift lever and extending forwardly therefrom and having a key, and also having a finger to release said dog; said auxiliary lever capable of operating the first lever to shift said shiftable member, and a temporary shift key lever at the other end of the keyboard connected to said shiftable member and having a connection to release said dog.

90 16. In a typewriting machine, the combination with a member to be shifted, of temporary and permanent shift-key levers connected to said member, a dog or hook to catch over a projection on the permanent shift-key lever to hold it down, said dog secured upon a rock shaft extending across the keyboard, a spring tending constantly to move said dog to effective position, and means on said temporary shift key to turn said rock shaft to release the dog; said temporary shift key mounted on the opposite end of the keyboard; and a second temporary shift key on the same side of the keyboard as the permanent shift key and also having means to release the dog.

110 17. In a typewriting machine, the combination with a member to be shifted, of temporary and permanent shift-key levers connected to said member, a dog or hook to catch over a projection on the permanent shift-key lever to hold it down, said dog secured upon a rock shaft extending across the keyboard, a spring tending constantly to move said dog to effective position, and means on said temporary shift key to turn said rock shaft to release the dog; said temporary shift key mounted on the opposite end of the keyboard; and a pin projecting from the side of the temporary shift key lever to engage an arm also fixed upon said

rock shaft, so that at every depression of said temporary key lever said rock shaft is rocked and the dog thereon is moved to releasing position.

5 18. In a typewriting machine, the combination with a member to be shifted, of temporary and permanent shift-key levers connected to said member, a dog or hook to catch over a projection on the permanent 10 shift-key lever to hold it down, said dog secured upon a rock shaft extending across the keyboard, a spring tending constantly to move said dog to effective position, and means on said temporary shift key to turn 15 said rock shaft to release the dog; said temporary shift key mounted on the opposite end of the keyboard, a pin projecting from the side of the temporary shift key lever to engage an arm also fixed upon said rock 20 shaft, so that at every depression of said temporary key lever said rock shaft is rocked and the dog thereon is moved to releasing position, and an auxiliary shift key lever pivoted upon said permanent shift 25 lever and having a finger to engage said dog to release it.

19. In a typewriting machine, the combination with a member to be shifted, of tem-

porary and permanent shift-key levers connected to said member, a dog or hook to catch over a projection on the permanent shift-key lever to hold it down, said dog secured upon a rock shaft extending across the keyboard, a spring tending constantly to move said dog to effective position, and means on said temporary shift key to turn said rock shaft to release the dog; said temporary shift key mounted on the opposite end of the keyboard, a pin projecting from the side of the temporary shift key lever to engage an arm also fixed upon said rock shaft, so that at every depression of said temporary key lever said rock shaft is rocked and the dog thereon is moved to releasing position, and an auxiliary shift key lever pivoted upon said permanent shift lever and having a finger to engage said dog to release it; said auxiliary lever extending forwardly from its pivot and bearing at its forward end a key and constructed to depress said permanent shift key lever.
